UNITED STATES PATENT OFFICE.

EDWARD G. FELTHOUSEN, OF BUFFALO, NEW YORK.

CHECK-VALVE INDICATOR.

SPECIFICATION forming part of Letters Patent No. 258,398, dated May 23, 1882.

Application filed December 13, 1881. (No model.)

To all whom it may concern:

Be it known that I, EDWARD G. FELTHOUSEN, of the city of Buffalo, in the county of Erie and State of New York, have invented a new 5 and useful Improved Check-Valve Indicator, of which the following is a specification.

This invention relates to an improvement in check-valves, whereby the operation of the valve is rendered visible. These valves are 10 arranged in conduit-pipes, such as the feed-pipes of steam-boilers, lubricators, stills, and of a great variety of apparatus to which water, oil, spirits, steam, and other liquids or fluids are conducted through such conduit-pipes by 15 pumps or injectors.

It is often very difficult, if not impossible, to determine whether the pump, injector, or other contrivance which moves the liquid or fluid is working properly.

20 The object of my invention is to provide a ready means whereby the operation of the pump or other impelling apparatus or the passage of the liquid or fluid through the conduit-pipe can be observed at a glance.

25 My invention consists to that end in combining with the check-valve an indicator which is set in motion by the check-valve, and which is inclosed in a transparent case or chamber so combined with the passage in which the 30 check-valve is arranged that the transparent chamber can be kept filled with a transparent liquid of heavier specific gravity than the liquid which passes through the conduit in which the check-valve is arranged, thereby rendering 35 the movements of the check-valve indicator visible when the liquid passing through the conduit is not transparent; also, of such a construction of the indicator that its movement is greater than that of the valve, whereby a slight 40 movement of the valve is rendered clearly visible; also, of certain details of construction of the indicator, as will be hereinafter fully described.

In the accompanying drawings, Figure 1 is 45 a side elevation of a check-valve provided with my improvement. Fig. 2 is a vertical section of the same. Fig. 3 is a horizontal section in line $x-x$, Fig. 2, showing the parts separated. Fig. 4 is a perspective view of the indicator 50 and the plate to which it is pivoted.

Like letters of reference refer to like parts in the several figures.

A represents the casing of a check-valve; B, the valve; b, the valve-seat; C, the inlet-pipe, and D the outlet-pipe. The upper portion of 55 the valve is provided with ribs or wings f, which slide in a cylindrical recess in the upper portion of the valve-casing, and whereby the valve is guided as it rises and falls.

g represents a stem which depends from the 60 under side of the valve and projects into a chamber, G, which is secured to the lower side of the valve-casing.

H represents an indicator-arm, which is arranged in a transparent case or chamber, I, and 65 which is set in motion by the check-valve. The case I is composed of a glass tube, i, and a slotted metallic tube, j, which surrounds the glass tube, and which is closed at its outer end and provided at its inner end with a screw-thread, k, by means of which it is secured in an opening, K, formed in the side of the chamber G.

The indicator-arm H is pivoted to a plate, L, and composed of a short arm, h, which bears 75 against the end of the valve-stem g, and a long arm, h', which is surrounded by the glass tube i. The plate L, to which the indicator H is pivoted, is placed against a shoulder or offset, l, which surrounds the opening K in 80 the chamber G at the bottom of the threaded collar k' thereof.

m represents a washer, of cork, rubber, or other suitable packing-material, which is interposed between the inner end of the glass 85 tube i and the plate L, and n is a packing-disk, of similar material, interposed between the outer end of the glass tube i and the closed outer end of the slotted metallic tube j. By securing the latter home tight joints are formed 90 at both ends of the glass tube.

The plate L is provided with a notch or opening, o, which fits over a projection, p, on the seat l of the plate, whereby the plate is secured in its proper position against turning. 95

As the valve rises and falls the short end h of the indicator H takes part in the movements of the valve, as it is held against the under side of the valve-stem g by the overhanging weight of the long arm of the indicator. The move- 100

ments of the valve-stem are rendered visible in an increased ratio at the end of the long arm of the indicator, whereby even a very slight movement of the valve—such as occurs, for instance, in the check-valves of lubricators—is easily distinguished. The transparent chamber I communicates with the interior of the valve-chamber.

If the liquid or fluid which passes through the valve-chamber is sufficiently transparent to render the indicator visible, such liquid or fluid may be permitted to fill the transparent chamber. If such liquid or fluid is not transparent, the chamber I should be filled with a transparent liquid of greater specific gravity, which will exclude the non-transparent liquid or fluid from the chamber I. For instance, if oil is pumped through the valve-chamber, the chamber I may be filled with water, which, by reason of its greater specific gravity, will prevent the oil from entering the chamber I and obscuring the indicator.

By observing the length of the arc through which the indicator moves the extent of the movement of the valve and the quantity of liquid passing through the conduits are easily ascertained.

A graduated arc may be arranged in the glass tube for the purpose of determining with exactness the distance through which the indicator moves.

I claim as my invention—

1. The combination, with a check-valve, of an indicator, means whereby an increased motion is imparted to the indicator, and a trans-

parent case which incloses the indicator and renders its movements visible, substantially as set forth.

2. The combination, with a check-valve provided with a stem, g, of the pivoted indicator H, composed of a short arm and a long arm, a chamber, G, inclosing the stem g of the valve and the short arm of the indicator, and a transparent chamber, I, inclosing the long arm of the indicator, substantially as set forth. 45

3. The combination, with the pivoted indicator H, of the chamber G, pivot-plate L, glass tube i, inclosing-tube j, washer m, and packing-disk n, substantially as set forth.

4. The combination, with the pivoted indicator H and transparent casing I, of the chamber G, provided with projection p, and pivot-plate L, having a notch, o, substantially as set forth. 50

5. The combination, with a check-valve, B, of an indicator set in motion by the check-valve and a transparent case which incloses the indicator, and which communicates with the chamber in which the check-valve is arranged by a passage located above the transparent case, whereby the latter can be kept filled with a transparent liquid of heavier specific gravity than the non-transparent liquid which passes through the check-valve chamber, and thus render the movements of the indicator visible, substantially as set forth. 60 65

EDWARD G. FELTHOUSEN.
